UNITED STATES PATENT OFFICE.

JULIUS PEGEL, OF NEW YORK, N. Y., ASSIGNOR TO THE HARTFORD CARPET COMPANY, OF HARTFORD, CONNECTICUT.

DESIGN FOR A CARPET.

SPECIFICATION forming part of Design No. 12,864, dated April 11, 1882.
Application filed February 23, 1882. Term of patent 3½ years.

To all whom it may concern:

Be it known that I, JULIUS PEGEL, of New York city, in the county and State of New York, have invented a new and original Design for Carpets, of which the following is a specification.

This invention relates to a new and original design for carpets and similar fabrics; and it consists in the novel grouping and configuration of figures hereinafter more fully described.

The accompanying photograph illustrates a face view of a carpet having my new design.

A floral group, A, springs from and partly conceals the lower portion of a rectangular field, B, (shown in part at each end of the photograph,) containing a ground of small squares, having centers resembling Greek keys placed diagonally, partially traversed by flower sprays from adjacent figures, and bounded by irregular right-lined ornamented borders. To the right of B, and above it, is the rectangular field C, (shown in part on each side of the photograph,) from the lower portion of which, and covering the same, springs the flower group D, whose sprays, like those of A, extend into the adjoining figures. C is filled with small ornamental squares, having cross-shaped centers partly traversed by flower sprays from contiguous groups, and is bounded by irregular right-lined borders. To the left of C, and above it, is the rectangular field E, from whose lower portion, and traversing it, springs the flower

group F, which extends its sprays over adjacent figures. E has a ground of diagonal interlocking fillet-work, is partly traversed by sprays from adjacent groups, and terminates in irregular right-lined borders. Below E, and to the left, is the rectangular field G, having a groundwork of ornamental squares, with square centers, traversed by sprays from adjacent flower groups and bounded by irregular right-lined borders. From the lower portion of G, and traversing the same, springs the flower group H.

I claim—

1. The design for carpets, consisting of the group A, substantially as shown. 45
2. The design for carpets, consisting of the group D, substantially as shown.
3. The design for carpets, consisting of the group F, substantially as shown. 50
4. The design for carpets, consisting of the group H, substantially as shown.
5. The design for carpets, consisting of the groups A D F H, substantially as shown. 55
6. The design for carpets, consisting of the ground B C E G, substantially as shown.
7. The design for carpets, consisting of the groups A D F H and ground B C E G, substantially as shown.

JULIUS PEGEL.
